UNITED STATES PATENT OFFICE.

KURT W. STEINHART, OF TACOMA, WASHINGTON.

STOVEPIPE.

1,253,902.

Specification of Letters Patent. Patented Jan. 15, 1918.

Application filed March 18, 1917. Serial No. 154,535.

To all whom it may concern:

Be it known that I, KURT W. STEINHART, a citizen of the United States, residing at Tacoma, in the county of Pierce and State 5 of Washington, have invented new and useful Improvements in Stovepipes, of which the following is a specification.

This invention relates to stove pipes, and more especially to the seam thereof; and 10 the object of the same is to produce a stove pipe section from a rectangular sheet of metal so that the finished section shall have an improved form of seam between the edges of the sheet.

15 This object is carried out in the manner hereinafter more fully described and claimed, and as shown in the drawings wherein:—

Figure 1 is a plan view of a stove pipe 20 section made in accordance with my invention, showing its bell end partly broken away and the male end of an adjacent section inserted therein.

Fig. 2 is a perspective detail of the female 25 end of one section, and

Fig. 3 is a perspective detail of the binder for contracting the bell end of the section as explained below.

Fig. 4 is a perspective detail of this end 30 of the section with the edges of the sheet bent into position ready to be connected, but not yet quite connected.

Fig. 5 is a transverse section on an enlarged scale taken on the line 5—5 of Fig. 1; 35 and

Fig. 6 is a sectional detail on the line 6—6 of Fig. 5.

Fig. 7 is a plan view of the blank from 40 which one of these improved stove pipe sections is made.

In Fig. 7 of the drawings the numeral 1 designates a blank of sheet metal from which one of my improved stove pipe sections is to be made. This blank is substantially 45 rectangular, being of a width to give the appropriate circumference to the finished section, and of a length measuring about twenty-two inches because that is the standard length of stove pipe sections now on the market. Nevertheless, I do not wish to be limited to the measurements, nor as to the material or its finish. This blank is to be constructed in such way that when its edges are brought together and connected 50 into a section of stove pipe, one end of the latter will be contracted slightly so as to

constitute the male end and the other end will be of such size as to slip over the male end, so that in effect it is the female end or bell end of the section; and adjacent each 60 end is stamped a bead whose outer projection constitutes a rib near the male end and whose inner side constitutes a groove near the female end. These beads are respectively numbered 2 and 3 in the drawings, 65 and need not now be again referred to. The lower end of the blank 1 shown in Fig. 7 is crimped or corrugated as at 4 so that eventually it may be reduced as seen at 5 in Fig. 1. At one end of the corrugated portion, which will be at one edge of the blank, 70 is cut a hole or opening 6, and in the other end is cut a V-shaped slit producing a triangular key 7 which eventually will engage said opening 6 to hold the extremity conical as seen at 5 in Fig. 1. Beyond the corresponding bead at the other end of the blank 1, the metal for the entire width of the blank is left plain as shown, but at the corners of the blank it is cut off oblique as 75 at 10 to produce a V-shaped notch 11 as seen in Fig. 2, and at the edges of this notch at the end of the blank are left lips 12 which are bent outward in the finished article as seen in Figs. 2 and 4. Coacting therewith 80 is a binder 13 best seen in Fig. 3, whose body is of substantially triangular shape with converging lips 14 along its side edges bent inward at angles slightly acute to the plane of its body. When now the female end of 85 one section is engaged over the male end of the next section, it is quite possible that in pushing the sections together until the rib and groove respectively engage, this end of the section will be strained open a 90 little, and in order to draw it again into its proper position the binder 13 is applied and its lips 14 engaged with the lips 12 and then the binder moved outward as indicated by the arrow in Fig. 1. The result will be 100 that when the binder reaches its final position as here indicated, the engaging lips will draw the bell end of one section closely around the body of the next adjacent section, while the beads will hold them together. 105

The seam for this improved pipe section is made up of male elements along one edge of the blank interengaging with female elements along the other. Near the left 110 edge as herein illustrated, the blank is bent on the line 20 to produce a leaf 21, and

again and reversely bent on the line 22 to produce a flap 23, and said leaf is pierced with a number of holes or slots 24, preferably substantially square as shown. Along 5 the right edge of the blank are cut pairs of L-shaped slits 25 producing interposed T-shaped keys 26 each having a narrow neck 27 uniting it with the body of the blank and a substantially square head which is a little 10 wider than the corresponding width of the hole 24 so that the side edges of the head must be bent up as seen at 28 in Fig. 4 in order that the head may pass through the hole. In forming the blank, the dies may 15 be such as will cut out the holes and the slits and perhaps will score the blank along the fold lines 20 and 22; and perhaps also the dies may be such as will bend up the edges 28 of the keys 26 as already described. 20 Now when the pipe section is to be made, the blank is bent and its edges drawn toward each other as seen in Fig. 4; and eventually each key is passed through its respective hole or slot so that when the parts are flattened out as in Fig. 6 the edges 28 will be 25 expanded beyond the corresponding edges of the slot and the key will become locked therein. In so flattening out the parts by means of suitable tools and machinery not 30 necessary to describe herein, the leaf 21 is folded down onto the body of the blank with the edges of the keys beneath it, and the flap 23 is folded down onto the shanks or necks 27 of the keys and the leaf 21 between 35 them. Thus is produced an extremely fine seam between the meeting edges of the blank, and the connecting portions of this seam may not be seen from the exterior as will be obvious from an inspection of Fig. 1. 40 The side edges of the blank can not move on each other relatively, to either contract or expand the size of the section or to bring said edges out of relative alinement with each other in any direction. 45 When this seam is employed in connection with the male and female ends of the stove pipe section already described, an article is

produced which is extremely serviceable, ready for immediate use, and withal practical and cheap to make. A special feature 50 of utility which the flap possesses, is that it covers the raw edges 28 of the keys and the necks 27 thereof and all irregularities which would otherwise project into the interior of the pipe section, and therefore a cleaning 55 instrument such as a brush may be subsequently forced through said section without catching on any projections. I might say in closing that it would be possible to use this improved seam on longer pipe sections 60 such as those used for spouting or in other places where sheet metal is appropriate for the pipe material and an absolutely watertight seam is not required.

What is claimed as new is:—

1. In a sheet-metal pipe section, a seam for uniting the edges of the blank, the same comprising a flap along one edge of the blank having spaced openings rectangular in shape, and correspondingly spaced T- 70 shaped keys along the other edge of the blank whose necks are integrally connected with such blank and whose heads are transversely longer than the width of said openings whereby they must be bent slightly to 75 pass through the openings, for the purpose set forth.

2. The herein described seam for sheet metal pipe sections and the like, the same comprising an element having a reversely 80 bent leaf along its edge and a flap beyond the leaf, the leaf being provided with a series of spaced openings rectangular in contour; of an element having along its edge a series of correspondingly spaced keys 85 of T-shaped contour whose necks are integrally connected with this element and whose heads are bent transversely for passage through said openings, the parts being subsequently compressed as described. 90

In testimony whereof I affix my signature.

KURT W. STEINHART.
